CRIMPING TOOL

William Roderick Over, Harrisburg, Pa., assignor to
AMP Incorporated, Harrisburg, Pa.
Filed Jan. 18, 1965, Ser. No. 426,257
5 Claims. (Cl. 29—203)

This invention relates to apparatus of the type intended for trimming the ends of wires and crimping open-sided electrical connectors onto the trimmed ends.

In the co-pending application of Richard Ellwood Reem, et al., Ser. No. 351,024, filed Mar. 11, 1964, there is disclosed an apparatus for crimping open-sided (open U-type) electrical connectors onto a wire end, or onto two or more wire ends, in a manner such that the ends of the wires are trimmed during the operating cycle of the apparatus and placed between the sidewalls of the connector immediately prior to crimping. Apparatus of the type disclosed in this Reem et al. application are particularly adapted to the making of splices between wires extending towards each other from opposite directions although apparatus of this type can also be used for crimping a single wire onto a terminal. The copending application of James Earl Marley et al., Ser. No. 391,087, filed Aug. 20, 1964, now abandoned, discloses and claims one type of splice connector intended for usage with the Reem et al. apparatus.

The present invention relates to an improvement to the apparatus of the above-identified Reem et al. application and particularly to an apparatus in which the manipulative steps of the operator are facilitated.

It is an object of the invention to provide an improved apparatus for trimming the ends of electrical conductors and crimping open U-type terminals onto the trimmed ends. It is a further object of the invention to provide an improved apparatus for making splice-type electrical connections. It is a further object to provide an apparatus for making splices involving more than two wires. A further object of the invention is to provide an apparatus for making electrical connections which facilitates the manipulative steps of the operator using the apparatus.

These and other objects of the invention are achieved in a preferred embodiment thereof comprising a crimping die and an anvil, the die having a channel or trough extending therethrough which is adapted to bend the sidewalls of an open-sided connector inwardly and towards each other during a crimping operation. A slot is provided in the die extending transversely of the axis of the trough and a shearing member is provided on the anvil which is movable into the slot. This shearing member is disposed between the die and anvil when the die and anvil are apart and moves into the slot concomitantly with movement of the anvil relatively towards the die. The arrangement is such that wires extending from opposite directions towards each other can be positioned between the die and anvil with the end portions extending into the slot in the die. Upon movement of the anvil relatively towards the die, the shearing member initially shears the excess wire in the slot by cooperation with the sides of the slot. Upon further movement of the anvil towards the die, the trimmed ends are positioned in the open U-type connector on the anvil and the sidewalls of the connector are folded over into the crimped engagement with the trimmed wire ends. The disclosed embodiment of the invention includes a means for separating wires where two wires extending

2

from the same direction are to be crimped in a connector and spliced to one or two wires extending from the opposite direction. The disclosed embodiment also includes a means in each end of the apparatus for clamping the wires being spliced during the critical portion of the crimping operation when the connector sidewalls are being folded into crimped engagement with wires. By virtue of this feature and other features of the disclosed embodiment described more fully below, the invention is particularly convenient to use where, for example, individual conductors in a telephone cable are being spliced in situ.

In the drawing:

FIGURE 1 is a perspective view of a preferred form of hand tool in accordance with the invention;

FIGURE 2 is a side view, with parts broken away, of the tool of FIGURE 1 showing the positions of the parts when the crimping die and anvil are in their opened positions;

FIGURE 3 is a view similar to FIGURE 2 but showing the positions of the parts when the die and anvil are closed at the end of a crimping operation;

FIGURE 4 is a view taken along the lines 4—4 of FIGURE 2;

FIGURE 5 is a view similar to FIGURE 4 but showing the positions of the parts at the completion of the crimping operation;

FIGURE 6 is a view taken along the lines 6—6 of FIGURE 4;

FIGURE 7 is a perspective view of an uncrimped splice connector of the type intended for usage with the disclosed embodiment of the invention;

FIGURE 8 is a perspective view of a completed splice; and

FIGURE 9 is a view similar to FIGURE 6 but showing the positions of the parts at the end of the crimping operation.

Referring first to FIGURE 7, a splice connector 2 in accordance with the general teachings of the previously identified Marley et al. application, Ser. No. 391,087, comprises a metallic channel member 4 of brass or other suitable conductive metal having sidewalls 6 extending from its longitudinal edges. A film 8 of insulating plastic material is provided on the external surface of channel member 4 for the purpose of insulating the completed splice connection as indicated at 2' in FIGURE 8. Two pairs of spaced-apart tangs 12, 14 are struck up from the web 10 of the channel 4, each pair being associated with one end of the connector. Spaced-apart slots 16 are provided in the tangs 12, 14, the width of these slots being such that their edges will penetrate the insulation of a conductor, when the conductor is forced downwardly into the slots, to establish contact with the metallic cores of the conductors. Advantageously, ears 18 are provided in the sidewalls 6 beside the pairs of tangs 12, 14 for the purpose of forcing the conductors down into the slots 16 when the sidewalls are bent inwardly towards each other.

The splice connector of FIGURE 7 is adapted to make a common connection among two pairs of wires 20, 22 which extend from opposite directions towards each other. In the finished connection, the wires 20 extend into the connector from one side thereof and through the slots 16 of the tangs 12 while the wires 22 extend from the opposite direction and through the slots of the tangs 14. It is not necessary to strip the insulation from the wire ends since

the electrical contact with the wires is established when they are forced downwardly towards the web 10 of the connector and into the slots 16 of the tangs as explained fully in the previously identified Marley et al. application.

Referring now to FIGURES 1 and 4, a preferred form of hand tool 24 in accordance with the invention comprises a two-part crimping die 26, 28 and an anvil 30 which is movable relatively towards and away from the die. The two parts 26, 28 of the die each have troughs extending therethrough which function to bend the sidewalls of the connector towards each other and towards the web 10 of the connector during such movement of the anvil towards the die. These troughs or channels have convergent surfaces on each side 34, 36 which merge with parallel surfaces 38, 40 (see FIGURE 6). The parallel surfaces, in turn, are reversely curved towards each other to form a central axially extending cusp 42. The two parts 28, 30 of the die are spaced apart to form a central slot 44 which intersects the trough-like forming surface and which extends in a plane disposed normally of the axis of these forming surfaces.

A shearing member in the form of a blade or block 46 is disposed between the die and anvil and extends transversely of the axis of the die and across the connector-supported surface 32 of the anvil. The thickness of this block is substantially equal to the width of the slot 44 and its edges 47 are advantageously made relatively sharp so that they can cooperate with the edges 49 of the die blocks 26, 28 to shear the ends of the wires being connected. Shearing blade 46 has a central cusp-like projection 48 on its upper surface which functions to assist in maintaining the separation between pairs of wires being spliced as will become apparent as this description proceeds. The blade 46 is secured to a base portion 54 of the anvil 30 by means of a depending arm 50 which extends downwardly behind the anvil (as viewed in FIGURE 4) and which is mounted on a pin 52 in the anvil base. The anvil 30 also has a depending arm 55 by means of which it is connected to the tool linkage.

As previously mentioned, the disclosed embodiment of the invention is adapted to crimp a first pair of wires 20 to a second pair 22 to form a common connection among the four wires involved. It is desirable to maintain separation of the pair 20 and the pair 22 while the individual wires are being moved relatively into the slots 16 of the tangs 12, 14. In order to maintain this separation during the crimping operation, there are provided a pair of spaced-apart wire separators 56 (FIGURE 6) one of these separators being associated with each of the die blocks 26, 28. These separators extend downwardly from the die blocks and centrally with respect to the forming surfaces 34-40 of the dies and are integral at their upper ends with guide members 58 which are slidable through slots 60 in the die blocks on each side of the central wire-receiving slot 44. The guide portions 60 of the separators extend downwardly beside the surface of a portion 68 of the tool frame and have a pin-slot connection 62 in their lower ends with the previously identified pin 52. The lower ends of guide portions 58 are inwardly bent as shown at 61 and bear against the upper ends of a pair of ears 86 on the tool frame. It will thus be apparent that there is a lost motion connection between the anvil and the separators and that the separators will be moved upwardly with the anvil after the lost motion, provided by the slots 62, has been taken up. At the end of the upward stroke of the anvil, the guide portions 58 move against springs 59 mounted in slots 74 of the head portion of the frame. When the common connection among four wires of the type shown in FIGURE 8 is to be made, each of the wires 20 is disposed on one side of the separators 56 on the left in FIGURE 4 and each of the wires 22 is disposed on one side of the separators on the right in this figure. The end portions of the wires are then led into the slot 44 as shown best in FIGURE 4.

The die blocks 26, 28 are secured by fasteners 70 to the

underside of a head portion 66 of a frame member 64. This frame member has a depending arm 68 to which handles 76, 82 are connected as described below. Head 66 has a central slot 72 in alignment with the slot 44 between the die blocks and has slots 74, as previously noted, in alignment with the slots 60 and in which the return springs 59 are disposed. As best shown in FIGURE 6, these return springs may take the form of simple wire springs mounted on pins disposed in the slots 74 and having arm portions locked in suitable notches on the sides of the slots 74.

The fixed handle 76 of the linkage system is secured at its upper end 78, 80 to the arm 68 of the frame. Handle 76 is of channel-shaped cross section and has sidewalls 77. A pin 84 extends between the sidewalls 77 and between a pair of spaced-apart ears 86 extending from the frame 68. The movable handle 82 is also of channel-shaped construction and is pivoted at its upper end to the pin 84, the sidewalls of the movable handle being nested within the ears 86 as best shown in FIGURE 4. Pin 84 extends through a slot 85 in the depending arm 55 of the anvil to permit relative upward movement of the anvil with respect to the frame 64.

The auxiliary handle 88 is pivoted intermediate its ends at 90 to the handle 82 and is pivoted at its inner end 92 to the lower end portion of anvil extension 55. This anvil extension has leftwardly extending ears 94 which extend between a pair of spaced-apart extensions 95 of the frame arm 68. Slots 98 are provided in the extensions 95 and a pin 96 extends through the ears 94 and into the slots 98. This pin-slot connection functions to guide the anvil extension 55 and the anvil along a rectilinear path towards and away from the crimping die during the closure of the handles.

The disclosed embodiment of the invention is intended to be used for the splicing of conductors of a telephone cable in situ or under similar circumstances where the conductors will be free hanging. In other words, the conductors 20, 22 in FIGURE 8 may extend indefinitely to the right and to the left and not be subject to close control by the operator during the crimping operation. It is desirable that the conductors being spliced should not be under any tensile stress during crimping and to avoid such stress and to isolate the end portions of the conductors I provide clamping means at each end of the anvil. These clamping means take the form of pressure pads 100 mounted on blocks 102 at the ends of the mandrel surface 32. The pads 100 cooperate with resiliently biased slide members 104 which are slidably mounted by pin-slot connections 108, 110, blocks 106 on each side of the frame head. The members 104 are urged downwardly by means of springs 112 which extend through slots on the rearward sides of the blocks 106. The springs 112 are formed from continuous length of wire which extends from an eye portion 114 secured to the back face of the head of the frame, as shown at 116. When the conductors are clamped (FIGURE 5) the concave surfaces of the pads 100 and the convex surfaces on the lower ends of the slide members 104 impart sinuous bends to the wires in the clamped zones thereof. These sinuous bends prevent, or at least limit, the transmission of tensile stresses to the portions of the wires to which the connector is being crimped.

In use, if it is assumed that the two wires 20', 22' in FIGURE 1 are to be spliced, the wires are merely led within the trough portions of the dies and through the slots 44, 72. In order to assist the operator in guiding the wires and positioning them in these slots, a pair of wire guide members 118 are provided on the front side of the frame head. These guide members comprise plates having forwardly extending flanges 120 which are pointed or tapered as indicated to form convergent surfaces 122 leading towards the slot 44 between the die blocks. The operator can thus grasp the ends of the two wires 20, 22 in his right hand and, while holding the tool in his

left hand, pull the wires towards the tool head so that they are guided by the edges 122 of the guides until the end portions of the wires are disposed in the aligned slots 44, 72. Positioning the wires in the tool is essentially the same as described above if four wires are to be spliced (FIGURE 8) excepting that the wires on each side of the splice must be separated with regard to the wire separators 56 as previously noted. Advantageously, a thumb piece 125 is provided on the front of the tool on the sidewalls of the fixed handle. This thumb piece is used by the operator while he holds the tool with his left hand and positions the wire in the slots 44, 72 with his right hand.

After the wires have been positioned, as in FIGURE 4, with their end portions in the slots 44, 72, the auxiliary handle 88 is moved in a generally clockwise direction about its pivotal axis 90 until this auxiliary handle is nested in the slot 124 of the handle 82. During this movement of the auxiliary handle, the movable handle 82 is also swung about its pivotal axis 84 and carried through part of its stroke. After the tool handles 88, 82 are brought into registry, the handles are moved as a unit through the remaining portion of the stroke of the handle 82 until the parts reach the positions shown in FIGURES 3 and 5. During such closure of the handles, edges 47 of the shearing member 46 move past the edges 49 of the die blocks 26, 28 thereby trimming the ends of the wires. Upon further movement of the anvil towards the die blocks, the uncrimped connector is carried into the troughs of the die blocks, the wires are moved into the slots 16 in the tangs 12, 14 of the connector, and the sidewalls of the channel are forced over against the wire and into the crimped relationship therewith. The wire separators 56 are moved upwardly, as viewed in FIGURE 6, during the latter portion of the stroke and after the lost motion permitted by the pin-slot connections 52, 62 has been taken up.

It should be mentioned that the springs 59 function to prevent upward travel of the separators beyond the position shown in FIGURE 9 if the pin 52 fails to move to the upper end of the slot 62 during upward movement of the anvil. For example, if the pin 52 and the guide portions 58 of the separators should remain in the relative positions of FIGURE 6 during upward travel of the anvil (as by reason of high friction between the parts), then the upper ends of the separators would move against the springs 59 prior to bending of the connector sidewalls. The separators would be prevented from further upward movement and the pin 52 would move relatively upwardly with respect to the guide portions 58. This feature is provided in order to assure the presence of the lower end of the separators in the vicinity of the connector during the actual bending of the connector sidewalls in order to prevent the wires from being improperly positioned while the sidewalls are being bent.

A salient advantage of the disclosed embodiment of the invention is the ease with which up to four wires can be positioned in the tool in preparation for crimping operation. The operator merely grasps the end portions of the wires and moves them past the edges 122 into the slots 44, 72 and then closes the tool handles in the manner previously described. The separators 56 will maintain the wires in separated condition and assure proper positioning of the wires with respect to the insulation piercing slots of the tangs. Finally, the clamping members at each end of the anvil 104, 106 firmly clamp the wires during the crimping operation to prevent the transmission of stresses to the wires while they are being crimped in the connector.

While the disclosed embodiment of the invention comprises a hand tool, the principles of the invention are equally applicable to usage with automatic or semi-automatic crimping devices of the type which are mounted on a suitable bench or other support. Under such circumstances, the hand tool linkage shown could be replaced by a suitable pneumatic or electric actuating mechanism.

It should also be added that the principles of the invention can also be used in tools adapted to crimp connecting devices other than splice-type connectors. For example, the trim and insert principle and the principles of the present invention can be used to crimp terminals of the ring-tongue type where a single wire is being crimped onto the terminal. Under such circumstances, one of the die blocks 26, 28 would be eliminated and a means would be provided for holding the ring-tongue end of the terminal during crimping.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

20 I claim:

1. Apparatus for trimming an end of a wire and crimping an open-sided connector onto said end comprising, a crimping die having trough-like forming surface portions for bending the sidewalls of said connector into crimped engagement with said wire, a crimping anvil, a slot in said die extending transversely of the axis thereof and intersecting said forming surface portions, a shearing member disposed between said die and anvil and in alignment with said slot, means rigidly connecting said shearing member to said anvil, and means for moving said anvil relatively towards and away from said die whereby, upon positioning said wire in said die with its axis extending parallel to the axis of said trough-like portion and with its end portion in said slot, and upon relative movement of said anvil towards said die, said shearing member moves into said slot, said end portion of said wire is trimmed, and said connector is crimped onto the trimmed end of said wire.

2. Apparatus for trimming ends of a pair of wires and for crimping an open-sided electrical connector onto said ends, said apparatus comprising, a crimping die having trough-like forming surface portions for bending the sidewalls of said connector into crimped engagement with said wires, a crimping anvil, a slot in said die extending transversely of the axis thereof and intersecting said forming surface portions, a shearing member disposed between said die and anvil and in alignment with said slot, means rigidly connecting said shearing member to said anvil, and means for moving said anvil relatively towards and away from said die whereby, upon positioning wires in said die with the ends of said wires disposed in said slot, and upon relative movement of said die towards said anvil, said shearing member moves through said slot, said wires are trimmed by said shearing member, and said connector is crimped onto said trimmed ends by said die.

3. A device as set forth in claim 2 including wire clamping means on each end of said die and anvil, said clamping means being closable upon movement of said die towards said anvil thereby to clamp wires being crimped between said die and anvil.

4. A device as set forth in claim 2 including wire guide means on one side of said die, said guide means comprising convergent guide surfaces on each side of said slot whereby wires being positioned in said slot can be led laterally along said surfaces from a side of said die.

5. Apparatus of the type intended for trimming a wire and crimping an open U-type ferrule forming portion of an electrical connector onto the trimmed end comprising, a crimping die, an anvil cooperable with said die to crimp said connector onto said wire, slot means in said die, shearing blade means normally disposed between said die and anvil and movable into said slot to trim the end portion of a wire extending between said shearing blade means and said die, a two part wire clamping means, one part of said clamping means being on said die and the other part thereof being on said anvil, said parts of

said clamping means being engageable with said wire during relative movement of said anvil towards said die whereby, said wire is clamped during crimping of said ferrule-forming portion.
